UNITED STATES PATENT OFFICE.

CHARLES E. WARD, OF CHARLESTON, WEST VIRGINIA.

WATER-TUBE STEAM-BOILER.

1,262,145.

Specification of Letters Patent.

Patented Apr. 9, 1918.

Application filed March 14, 1916, Serial No. 84,082. Renewed March 1, 1918. Serial No. 219,898.

To all whom it may concern:

Be it known that I, CHARLES E. WARD, a citizen of the United States, residing at Charleston, in the county of Kanawha and State of West Virginia, have invented certain new and useful Improvements in Water-Tube Steam-Boilers, of which the following is a specification.

This invention relates to watertube steam boilers, more particularly to those watertube boilers provided with upper and lower headers connected by sets or banks of tubes, one bank being above the other with a baffle plate or plates arranged between them, and 10 the whole so arranged that upon the boiler being fired, the circulation is established upwardly by way of one bank of tubes, usually the lower bank, and downwardly through the tubes of the other bank of tubes. 15 The object of this invention is the production of a watertube steam boiler of the character mentioned wherein the parts are of special construction, proportion and arrangement with respect to each other, and 20 wherein more than one pair of banks of tubes are employed, one pair of banks of tubes being arranged above another. It is believed that a material increase in steaming efficiency is attained by the particular construction and arrangement of the parts herein set forth. 25

Of the accompanying drawings illustrating this invention, Figure 1 represents a watertube steam boiler constructed in accordance with this invention, and shown in vertical section, the section extending from front to rear of the boiler. Fig. 2 is a vertical transverse section of the lower header taken on the broken line $x-x$ of Fig. 1, and showing 30 the pairs of banks of tubes, with the positions of the interposed baffle plates. Fig. 3 is an enlarged vertical section of the upper portion of the lower header, showing the sectional downflow divider plate and the 35 supporting and guiding means therefor, and the connection with one wall of the header. Fig. 4 is a cross-section, horizontally, on the broken line $y-y$ of Fig. 3, the same scale of drawings being retained. The same letter 40 refers to the same part.

Considering the drawings, in Fig. 1 there will be noted exposed to the furnace A, a row of lower tubes a , which support the baffle plate or plates B. The door of the furnace is adjacent to the lower header b , and 45 the lower bank of tubes C incline upwardly

and rearwardly, from the lower header b to the upper header c . The lowest or first baffle plate B has one end in contact with or near the lower header. 60

Above the lowest bank of tubes C and resting thereon is a second baffle plate D, having one end against or near the upper header c . The baffle plates may in practice be formed of sections laid across the 65 tubes, but, as a whole, each baffle plate extends lengthwise of the tubes from a position against or near one of the headers.

Above the second baffle plate D is the second bank of tubes E, the tubes being the 70 same in number and size as those of the bank C. The banks of tubes C and E are considered in this description as a pair of banks of tubes, and they are the lower pair of banks of tubes as illustrated in Fig. 1 of 75 the drawings.

Upon the tubes E is supported the third baffle plate F, having one end near or against the lower header.

Connecting the headers above the baffle 80 plate F is the upper pair of banks or tubes. Of the upper pair, the lower member or bank G carries the fourth baffle plate H, and the bank of tubes J, arranged above the baffle plate H is the complemental member of 85 the upper pair of banks. It will be observed that the upper pair of banks of tubes comprises less number of tubes than the banks of the lower pair of banks of tubes, and there is less passage area between the upper baffle plates, as the hot gases from the 90 furnace give off some portion of their heat to the lower pair of banks of tubes and contract correspondingly in volume. Above the bank of tubes J and usually supported thereby is a fifth baffle plate j , having one end against or near the lower header, and by which the hot gases are directed to the exterior through the top of the casing of the 95 boiler. 100

Connected with the lower header at the top thereof is the drum K, and a number of tubes, such as the tube L, connect the drum and the upper header. In passing out, the hot gases pour over and around the tubes L. 105

As best shown in Figs. 3 and 4, the lower header b has within it near the top a removable, sectional downflow divider plate M. The sections of the plate M are supported at the bottom and connected with the wall of 110 the header by the curved bracket plate N, and the sections are held in vertical position

in the vertical grooves *m* in the vertical partitions *O* that divide the headers into vertical chambers, as illustrated also in Fig. 2, in which figure the relative arrangements of 5 the banks of tubes and the baffle plates are set forth. It will be noted that the curved bracket plate *N* connects the downflow divider plate with the wall of the header just below the bank of tubes *G*, which is the 10 lower bank of the upper pair of banks of tubes, and the purpose is to divide the downflow of the circulating water and the feed water between the pairs of banks of tubes. It will be understood that each vertical 15 chamber of the header is provided with the sectional plate *M* and the curved or inclined supporting bracket *N*. It will also be understood that the plate *M* may comprise any 20 number of sections, according as the necessity arises for a high or a low downflow divider plate. Ordinarily, the sections of plate *M* extend to the top of the header, and they may be introduced into the grooves *m* or removed therefrom by reaching into the 25 drum with the hand or suitable tool.

In explaining the operation of this invention, let it be assumed that a steam boiler constructed in accordance therewith is fired up. It is found in practice, and it has been 30 definitely determined by trial, that two independent circulating systems are established in the one body of water contained by the boiler. The directions of the circulations in the two systems are indicated by the broken-line arrows. In the lower pair of banks of 35 tubes, the circulation is upward through the tubes *C* and downward through the tubes *E*. In the upper and lesser pair of banks of tubes, the circulation is upward through 40 tubes *G* and downward through the tubes *J*. Not only is the circulation thus established and maintained, but, it is particularly rapid, and, the circulation in the lower pair of banks of tubes is very quickly set up, making 45 the boiler constructed in accordance with this invention a very quick steamer. The feed water or other downflow from the drum *K* is divided by the plate *M* between the pairs of banks of tubes, as is believed to have 50 been clearly set forth hereinabove.

Having now described this invention, and

explained the mode of its operation, what I claim is:—

1. In a watertube boiler, the combination with upper and lower headers, of a drum 55 connected with the lower header, upper and lower banks of tubes connected with the headers, and a downflow divider plate arranged in the upper portion of the said lower header and connected with the inner 60 wall of the header above the ends of said lower bank of tubes and below the ends of said upper bank of tubes, the said downflow plate being constructed with removable sections whereby there may be formed in the 65 header a downflow divider plate of greater or less height from its said connection with the wall of the header.

2. In a watertube steam boiler, the combination with a header having internal vertical partitions dividing the header into vertical chambers, the said partitions being each provided with vertical grooves, of removable downflow divider plates movably fitting the said grooves in the partitions in 75 each chamber of the header, and bracket plates in each chamber constructed to support the said divider plates in the said grooves, the said bracket plates being attached to a wall of the header in each chamber and constructed to close the space between the bottom of the said divider plates and the said wall.

3. In a watertube steam boiler, the combination with a header having internal vertical partitions dividing the headers into vertical chambers, the said partitions being each provided with vertical grooves, of removable downflow divider plates each comprising separable sections movably fitting 85 the said grooves in the partitions in each chamber of the header, and bracket plates in each chamber constructed to support the said sections of the divider plate in the said grooves, the said bracket plates being attached to a wall of the header in each chamber and constructed to close the space between the bottom of the lowest section of 90 the said divider plate and the said wall.

In testimony whereof I affix my signature. 95

CHARLES E. WARD.
